UNITED STATES PATENT OFFICE.

FRANK G. RUF AND WILLIAM KLESIUS, OF NEW YORK, N. Y.

TANK-SIPHON.

1,256,928.

Specification of Letters Patent. Patented Feb. 19, 1918.

Application filed April 4, 1917. Serial No. 159,762.

To all whom it may concern:

Be it known that we, FRANK G. RUF, a citizen of the United States, and a resident of the city of New York, borough of Manhattan, in the county and State of New York, and WILLIAM KLESIUS, a citizen of the United States, and a resident of the city of New York, borough of Bronx, in the county of Bronx and State of New York, 10 have invented a new and Improved Tank-Siphon, of which the following is a full, clear, and exact description.

Our invention relates to tank siphons particularly adaptable for water-closet tanks. An object of the invention is to provide an inexpensive and efficient device which is simple in construction and which will not get out of order easily.

With the above and other objects in view, 20 the nature of which will more fully appear as the description proceeds, the invention consists in the novel construction, combination and arrangement of parts as herein fully described, illustrated and claimed.

25 In the accompanying drawings, forming part of the application, similar characters of reference indicate corresponding parts in all the views.

Figure 1 is a section through a tank provided with an embodiment of our invention, a portion of which is shown in section to illustrate the details of construction;

Fig. 2 is a horizontal section on line 2—2, Fig. 1; and

35 Fig. 3 is a similar section on line 3—3, Fig. 1.

Referring to the drawings, the siphon is in the shape of an inverted U, the shorter leg 5 of which has a by-pass 6 at the open 40 end thereof, while the longer leg 7 is reduced in cross section from a point between the spill 8, which is formed between the two legs, and the end of the shorter leg. Preferably the diameter of the shorter leg 45 and the wider portion of the longer leg are substantially alike.

A piston 10 having a loose fit in the leg 5 is provided with guides 11 to prevent the binding of the piston within the leg 5 of 50 the siphon. The guide 11, which is of tubular form, has apertures 12 which register with a cut-away 13 in the leg 5, which forms the spill. A connecting rod 14 unites the piston 10 to an arcuated arm 15 which 55 extends from a longer arm 16 of a bell-crank lever 17. The bell crank is pivotally sup-

ported on an extension 18 from the siphon. The shorter arm 19 of the bell-crank lever may be connected to a suitable flexible member 20 for operating the bell-crank lever. 60 The motion of the lever on its pivot is limited by stops 21 provided on the extension 18.

The curvature of the arcuated arm 15 is such that it will swing into the shorter 65 siphon leg 5 without interference and bring the piston 10 against the top 22 of the siphon. By providing a bell-crank arm having an arcuated extension, we eliminate a pull rod from the piston through the top 70 of siphon, which requires a packing which, after wear, allows air to pass into the siphon and interfere with the working of same. This lever arrangement also permits a large 75 lift with a comparatively small pull on the flexible member 20.

The upward displacement of the piston will force over the spillway 9 the volume of water inclosed between the level A of the water in the tank and the top of the by-pass 6 of the 80 shorter siphon leg 5. As this volume of water is always larger than the volume of the non-restricted section of the longer siphon leg 7, the flow in the longer leg 7 will be checked by the restricted section 8 thereof, thereby insuring the starting of the siphon by even the slowest possible displacement of said piston. The suction caused by the outflow of the fluid will maintain the piston 10 at the top 22 against gravity upon it and upon the 85 bell-crank lever until the air begins to pass through the slot 23 provided at the end of the shorter siphon leg 5 for the arcuated extension 15 of the bell-crank lever 17. The entering air will allow gravity to restore 90 the piston 10 to its normal position; the siphon action will be broken and permits the restitution of the level A in the tank. 95

While we have described the principle of operation, together with the device which 100 we now consider to be the best embodiment thereof, we desire to have it understood that the device shown is merely illustrative and that such changes may be made as are within the scope of the appended claims. 105

We claim:

1. A tank siphon in the shape of an inverted U having a shorter leg and a longer leg, a piston in the shorter leg, a bell-crank lever having an arcuated extension from the 110 longer arm of the bell-crank lever, a connecting rod uniting the arcuated extension

to the piston, and flexible means engaging the shorter arm of said bell-crank lever for operating the same.

2. A tank siphon in the shape of an inverted U having a shorter leg and a longer leg, a piston in the shorter leg, an extension from the siphon, a bell-crank lever pivotally mounted on said extension, an arcuated extension from one arm of the bell-crank lever, a connecting rod uniting the arcuated extension to the piston, and a flexible member engaging the other arm of the bell-crank lever for operating the same.

3. A tank siphon in the shape of an inverted U having a shorter leg and a longer leg restricted in cross section in the lower part thereof from a point above the end of the shorter leg, a piston in the shorter leg, a pivotally-mounted bell-crank lever having a shorter and a longer arm, an arcuated extension from the longer arm, a connecting rod uniting the arcuated extension to the piston, and a flexible member engaging the shorter arm.

25 4. A tank siphon comprising an inverted U having a shorter leg and a longer leg restricted in cross section in the lower part thereof from a point above the end of the shorter leg, a piston for the shorter leg, said shorter leg having a by-pass in the lower end thereof to allow the entrance of

a fluid into said leg when the piston is at its lowermost position in the leg, a pivotally mounted bell-crank lever having a longer and a shorter arm, an arcuated extension from the longer arm, a connecting rod uniting the arcuated extension to the piston, a flexible member engaging the shorter arm for operating the bell-crank lever, the curvature of said arcuated extension being such as to bring the piston to the top of the inverted U without interference of said arcuated member with the shorter leg, and means for engaging the arms of the bell-crank lever for controlling its movement. 45

5. A tank siphon in the shape of an inverted U having a shorter and a longer leg, a piston in the shorter leg, an extension from the siphon, a bell-crank lever pivotally mounted on said extension and having a shorter and a longer arm, an arcuated extension from the longer arm of the bell-crank lever, a connecting rod uniting the piston to the arcuated extension, a flexible member connected to the shorter arm for operating the bell-crank lever, and means on said extension for engaging the shorter and the longer arms of the bell-crank lever at the extreme positions thereof. 55
